UNITED STATES PATENT OFFICE

EDMUND H. FARQUHAR, OF SCHENECTADY, NEW YORK, ASSIGNOR TO GENERAL ELECTRIC COMPANY, A CORPORATION OF NEW YORK.

TURBINE BUCKET.

1,003,892.

Specification of Letters Patent. Patented Sept. 19, 1911.

Application filed March 9, 1910. Serial No. 548,218.

To all whom it may concern:

Be it known that I, EDMUND H. FARQUHAR, a citizen of the United States, residing at Schenectady, county of Schenectady, State of New York, have invented certain new and useful Improvements in Turbine Vanes or Buckets, of which the following is a specification.

This invention relates to vanes or buckets for elastic fluid turbines, and its object is to cheapen the cost of manufacture, increase the strength of the bucket, obviate the necessity of using separate space blocks, and lessen the liability of the bucket to become loose in the wheel rim.

As ordinarily made, the bucket is cut from a strip of extruded metal alloy. One end is milled away to leave a tenon to receive the covering strip; the other end is machined to form a shank having a dovetail shape to engage the under cut groove in the wheel rim. The shoulders of this dovetail are subjected to severe strain owing to the centrifugal force developed by the bucket when the wheel is revolving at high speed. These shoulders are necessarily cut from the thinner edge portions of the extruded strip, but my invention provides a greater thickness of metal at these points and consequently greater strength. It is customary to space the buckets apart by inserting separate blocks between the shanks, but I avoid this by making the spacing members integral with said shanks. Furthermore, the construction of my improved shank is such that it has a certain resiliency, and when forced into the groove in the wheel rim it tends to hold itself therein and is less liable to become loose. I accomplish these results by punching out a bucket blank from sheet metal, the dovetail portion of the shank being provided with lateral wings or extensions which are folded over upon the middle portion and thus provide shoulders three times as thick as the shank proper. Moreover, when such buckets are assembled, the folded-over portions serve as spacing blocks to insure the requisite distance between the blades of said buckets. The folded-over wings are not welded or brazed to the shank, so that their free ends can yield somewhat when the bucket is forced into the curved groove in the wheel

rim, and will thus by their resilience assist in holding the bucket firmly in place.

In the accompanying drawing, showing one of the embodiments of my invention, Figure 1 is a side elevation of a portion of the bucket-wheel of an elastic fluid turbine, partly broken away to show my invention; Fig. 2 is a cross-section of the same; Fig. 3 is a transverse section through the buckets parallel with the wheel rim; and Fig. 4 shows the blank for a bucket.

In forming the buckets 1, I take a plate 65 of sheet metal, for example a steel plate containing about 30% nickel, or bronze or the like, and of a thickness corresponding to that of the middle portion of the completed buckets. From said plate, by means 70 of dies, I punch blanks, similar to that shown in Fig. 4, having a blade portion 2, a tenon 3, and cuts extending inwardly from both sides to form a shank 4 and lateral wings 5 on said shank. If inclined shoulders or dovetails 6 are formed on the shank, the wings also have corresponding inclines or chamfers 7 which register with the shoulders 6 when said wings are folded over upon the shank, one on the front and the other on 80 the back, as shown in Fig. 3. It will be noted that when the vanes or buckets are assembled in place that each shoulder on the vane engages one wall of the under cut groove, and that each wing engages both 85 walls of said groove. In other words the fold engages one wall and the free end the other thus rigidly securing the vanes in place. Furthermore it will be noted that said folded portions are parallel to each 90 other and do not partake of the curvature of the vanes. Since the end of the fold engages one vertical wall of the groove and the free end the opposite wall, the base will prevent the vane from moving sidewise in 95 the groove. Said movement is also resisted by the side walls of the shank proper engaging the walls of the throat of the groove. The body 1 is shaped in dies to give it the proper curvature, as seen in Fig. 3, and its 100 edges 8 are ground or otherwise sharpened.

The wheel rim is preferably composed of segments 9, fastened to the web 10 of the wheel by the transverse rivets 11 passing through the segment and the web, or it may 105 be fastened by other suitable means. In the

periphery of each segment is formed an undercut groove to receive the shanks of the buckets, which are slid into said groove from the ends. The shanks with their folded-over wings completely fill the undercut part of the groove, abutting solidly together as shown in Figs. 1 and 3. The chamfered shoulders of the dovetail portion of each shank and its wings afford a wide, strong bearing for the bucket, ample to resist all centrifugal strains. The wings, free at one end, adapt themselves to the curvature of the groove and by their resilience assist in holding the buckets tightly.

15 There are vacant spaces between the buckets above the folded-over wings, which if left open would produce wasteful eddies in the columns of steam flowing through the wheel. I therefore cover these spaces with plates 12 of sheet metal, notched to fit around the shanks of the buckets and having their edges abutting. These plates rest in rabbets cut along the edges of the groove in the wheel segments, as plainly shown in 20 Figs. 2 and 3, so that a smooth unbroken surface is presented across which the steam can flow without obstruction.

In accordance with the provisions of the patent statutes, I have described the principle of operation of my invention, together with the apparatus which I now consider to represent the best embodiment thereof; but I desire to have it understood that the apparatus shown is only illustrative, and 35 that the invention can be carried out by other means.

What I claim as new and desire to secure by Letters Patent of the United States, is,—

1. A bucket for an elastic fluid, turbine punched from sheet metal with portions integral with its shank that are folded over against the back and front of said shank to form a base.
2. A turbine bucket punched from sheet metal and having spacing members integral with its shank that are folded over to form with said shank a base composed of three thicknesses or layers of metal.
3. A turbine bucket punched from sheet metal and having its shank provided with lateral wings that are folded over upon the opposite faces of said shank.
4. A turbine bucket punched from sheet metal and having its shank provided with folded-over wings, said shank and wings having chamfered shoulders.
5. In a turbine, the combination with a rim having an undercut groove, of buckets made of sheet metal and having shanks pro-

vided with folded-over wings, said shanks 60 and wings having shoulders engaging the undercut of said groove.

6. In a turbine, the combination with a rim having an undercut groove, of sheet metal buckets having shanks provided with 65 folded-over wings, and plates inserted between said buckets flush with the surface of the rim.

7. In a turbine, the combination with a rim having an undercut groove, of sheet 70 metal buckets having shanks provided with folded-over wings, and plates inserted between said buckets and having notches fitting around said shanks.

8. A blank for a turbine bucket punched 75 from sheet metal and having a body portion provided with a tenon, an integral shank, and wings extending from said shank and adapted to be folded over upon the same.

9. In a turbine, the combination with a 80 rim having an undercut groove of buckets whose shanks are located in the groove, each of said shanks having a base formed by bending over the stock of which it is composed, the fold in the stock and the free 85 ends of the bent-over portions both engaging with the walls of the groove.

10. A turbine bucket having a centrally disposed shank projecting from one end of the bucket and provided with resilient portions integrally united to the lateral edges of the shank.

11. A turbine bucket having a shank provided with a plurality of integral resilient portions extending parallel to the shank and serving as spacing blocks.

12. A turbine bucket having a shank at one end provided with a narrow portion next the bucket and a wider portion beyond the first portion, and wings integrally united 100 with the lateral edges of the second portion that have the same shape and size as said second portion and are bent over into juxtaposition and alinement with said second portion to form a base for the bucket.

105 13. A turbine bucket having a shank projecting from one end of the bucket with a portion integrally united to the lateral edge of the shank that is bent into juxtaposition to said shank to form with it a 110 base for the bucket.

In witness whereof, I have hereunto set my hand this 3rd day of March, 1910.

EDMUND H. FARQUHAR.
